SHOE REPAIRING MACHINE

Harry R. Myers, Zanesville, Ohio

Application December 4, 1939, Serial No. 307,533

8 Claims. (Cl. 12—33)

This invention relates to an improved shoe repairing machine of the general type shown in my patent, No. 2,129,437, granted September 6, 1938.

As one of its principal objects, the invention seeks to provide a shoe repairing machine which may be operated with the utmost facility for cementing patches or taps to shoe soles.

Another object of the invention is to provide a machine of this character including an anvil having a resilient heating surface for conveniently receiving the shoe sole.

A further object of the invention is to provide a shoe repairing machine wherein the anvil may be readily removed from the machine when desired.

As a further object, the invention seeks to provide a shoe repairing machine having a base provided with a standard, the standard having an overhanging stationary head, and said head having improved means thereon for supporting a shoe whereby the shoe may be shifted toward and away from the anvil and, when being moved away from the anvil, by further movement, may be shifted to a position to permit convenient removal of a repaired shoe.

As a further object, the invention provides a shoe repairing machine wherein the means carried by the head consists of an operating lever, a shoe supporting element, linkage connecting the operating lever with the shoe supporting element, and a spring for resiliently mounting the shoe supporting element with respect to the head.

Other and incidental objects of the invention will become apparent during the course of the following description.

In the drawings forming a part of my application:

Figure 1 is a side elevation showing my improved shoe repairing machine as it would appear preliminary to being placed in operative position, the head, shoe supporting element, and operating links and lever structure also being shown, in dotted lines, in a raised position for permitting removal of a shoe after repair thereof.

Figure 2 is a side elevation of the machine in operative position, a shoe being shown in section as it would appear in proper position on the anvil.

Figure 3 is a top plan view of the machine in inoperative position.

Figure 4 is an enlarged vertical sectional view on the line 4—4 of Figure 3.

Figure 5 is an enlarged vertical sectional view showing the head with the plunger and stem employed in the position assumed when the machine is in operation.

Figure 6 is an enlarged detail sectional view, partly shown in elevation, of the structure of one of the heads employed.

Figure 7 is a vertical sectional view on the line 7—7 of Figure 3.

Figure 8 is a top plan view, a portion of the bottom plate being broken away to show the thermostat, and

Figure 9 is a longitudinal sectional view on the line 9—9 of Figure 3.

Referring now more particularly to the accompanying drawings wherein similar numerals of reference will be seen to designate like parts throughout the various views, the numeral 1 indicates in general the base of my improved machine. The base 1 is preferably formed of heavy cast metal and is of substantially rectangular contour. Said base has a standard 2 formed integrally therewith and rising from one side thereof, said standard including a forwardly and medially disposed web 3 and lower flanges 4 and 5 which lower flanges are formed integral with the base. The base also includes vertically enlarged end walls 6 and 7 which cooperate with the web 3 to define compartments 8 and 9. The compartments 8 and 9 removably receive shoe supporting anvils 10 and 11 which will be described more fully hereinafter. The standard 2 carries a bracket 12 at its upper end, said bracket extending longitudinally above the base in spaced relation thereto and carrying head mounting plates 13 and 14.

Movably mounted on the head mounting plates 13 and 14 are heads 15 and 16. The heads 15 and 16 are of identical construction so that a description of one will suffice for both. The head 15, for example, is mounted on the plate 13 and is thus disposed above the anvil 10 substantially medially of the length thereof. Said head includes a body portion 17 which is substantially rectangular in shape, said body portion having a front wall 18 which is removably connected therewith. As best seen in Figure 4 of the drawings, the body 17 is formed with a longitudinally extending opening 19 which is substantially rectangular in cross section. Said body 17 is also formed with a recess 20, opening on one side edge of the body, and said recess is connected with the upper and lower faces by means of bores 21 and 22. The plate 13 forms the back of the head 15 so that no back wall will be required for said head. A slot 23 communicates between the opening 19 and the rear of the head.

Slidably mounted in the opening 19 is a plunger 24 which plunger carries a stop pin 25

at its upper end, said stop pin being normally slidably mounted in the slot 23. The plunger 24 is, as best seen in Figures 1 and 2 of the drawings, extended downwardly to a point beneath the head. As shown in Figure 1, the rear face of the lower end of the plunger is formed with vertically spaced recesses 26 which are selectively engageable by the inner end 27 of a set bolt 28 which set bolt is carried on the apertured and squared upper end 29 of a shoe supporting element 30. As seen, the shoe supporting element is of arcuate contour, and said shoe supporting element carries a toe or last 31 which is engageable with the upper surface of a shoe sole within the shoe. That is to say, when a shoe is, as best seen in Figure 2 of the drawings, held in operative position, the plunger is forced downwardly for clamping the shoe sole between the upper surface of the anvil 11 and the lower surface of the toe 31 of the element 30. The manner of shifting the plunger downwardly will now be described.

Extending through the bores 21 and 22 and through the recess 20 is a stem 32. The stem 32 is movably mounted in the bores and carries a squared collar 33 which collar is rigidly fixed to the stem and is, therefore, limited against movement thereon. The collar, as best seen in Figure 3 of the drawings, extends through a slot 34 in the wall 18 and is vertically movable, with movement of the stem, throughout the length of the slot. Confined between the collar 33 and the upper limits of the recess 20, and surrounding the stem 32, is a coiled spring 35, said spring normally urging the collar downwardly into engagement with the lower limits of the recess 20.

For manually forcing the plunger downwardly, I provide an operating lever 36 which is formed with a manually engageable portion 37 and an arm 38 which is disposed in obtuse angular relation with respect to the manually engageable portion 37. A pivot bolt 39 extends through the lever 36 at the junction of the arm with the manually engageable portion and said bolt extends through the lower end portion of the plunger 24. The arm 38 has its free end portion operatively connected with one end portion of a link 39 by means of a bolt 40. Said link 39 is extended downwardly, as clearly seen in Figure 1, to define a stop lug 41 which is engageable with the hub 42 of the lever 36, said hub being formed to receive the bolt 38a therethrough. As will be seen, the stop 41 limits forward and downward movement of the operating lever to such an extent that, in lowermost position, the manually engageable portion 37 will be substantially horizontal with respect to a horizontal supporting surface. The opposite end of the link 39 is connected to the collar 33 by means of a bolt 43. It will now be understood that the operating lever 36 is not only connected with the plunger 24 but is also connected with the stem 32, through the collar 33 and the link 39. With further reference to the link 39, it should be observed that the lug 41 is slightly angularly disposed with respect to the body of said link so that, before the end of the lug engages the hub 42, when the lever is in lowered position, the axis of the bolt 40 will be moved forwardly past dead center. In this condition, the link 39 will cooperate with the arm 38 for tending to urge the manually engageable portion downwardly. The link 39, of course, will be urged upwardly against the tension of the spring 35, said spring providing means for forcing the plunger downwardly un-

der tension. As previously stated, and as shown in dotted lines in Figures 1 and 7 of the drawings, the head 15 is movable for disposing the shoe supporting element 30 upwardly and forwardly with respect to the bracket 12 so that a shoe may be readily removed therefrom after repair. In order to effect this, the plate 13 is formed as shown in Figures 1 and 7. That is to say, said plate 13 includes a straight portion 44 which is normally disposed to confront the rear edge of the slot 23 in such a manner that the pin 25 will be permitted to slide vertically within the slot and against the front face 44. The plate 13 is, however, formed with a downwardly extended arcuate face 45 which terminates at its lower end in a stop shoulder 46. The forward and upper ends of the arcuate face 45 are disposed near the upper end of the slot 23 so that, when the plunger 24 is retracted to its uppermost position, the pin 25 will pass the upper limits of the front face 44. The entire head will be then permitted to swing about a pivot bolt 47 which extends through the head and through said plate 13. The pin 25 will thus be permitted to slide over the face 45 and, as shown in dotted lines in Figure 7, said head will be limited against pivotal movement by engagement of said pin 25 with the shoulder 46. In this position, the shoe supporting element will be disposed with the last or toe 31 in a forward raised position so that the shoe may be conveniently removed. Downward movement of the head is limited by means of a stop pin 48 which is carried by an ear 49 formed on the lower and rear extremities of the plate 13.

Further description of the anvils 10 and 11 will now be given. It is desired to point out that the anvils are of identical construction so that a description of one will suffice for both. The anvil 11, for example, comprises a substantially U-shaped frame 50. The frame 50 includes a depressed central portion which defines a well 51 for the reception of water or other liquid. A drain bore 52 leads from the well and is normally closed by a screw plug 53. The well 51 is provided with a thickened bottom wall 54 which is formed with a recess 55 in its lower surface for the reception of a heating element 56. At one end the recess 55 is slightly enlarged, at 57, to receive a thermostat unit 58. A plate 59 closes the recess and securely retains the heating element and thermostat unit in place. The portion 57 of the recess 55 has contact springs 60 and 61 mounted therein, said contacts being electrically connected with the heating element 56, the contact 60, however, being connected through the thermostat unit 58. Pairs of insulated studs are shown at 62, one of said studs being provided for engaging each of the springs 60 and 61, the studs 62 being connected in an electric circuit with a source of electrical current and a control switch.

The well is covered by a tread 63 which is formed of rubber or other resilient material, said tread having its upper end edges held in place on the frame 50 by means of clips 64 and 65. Clips 66 engage each side edge of the tread. The clips securely fasten the tread in position so that liquid contained in the well will be prevented from escaping from between the ends of the tread and the ends of the frame. The tread will, of course, provide a resilient support for a shoe.

Screws 67 are passed through the front and rear walls of the base 1 and engage each anvil and retain it in operative position. As will be seen, two screws are carried in the front of the base and one at the rear. This arrangement, of

course, permits proper location of the anvils with respect to the base.

The operation of the invention would appear obvious from the foregoing description. However, it is deemed advisable to insert a brief statement concerning said operation. Preliminary to placing a shoe to be repaired in position, the lever 36 is raised so that the plunger 24 will be retracted to its full uppermost position. The manually engageable portion 37 will be disposed vertically and the shoe engaging element 30 will be disposed between the head and the anvil and out of engagement with said anvil. The spring 35 will, of course, urge the stem 32 to its lowermost position. If found more convenient, the lever 36 may be forced rearwardly for causing the pin 45 to ride over the base 25 and into engagement with the shoulders 46, when the head will be shifted to horizontal position and the last or toe 31 shifted to vertical position. The machine is now ready for the placing of a shoe on the toe or last, it being a matter of choice whether the head is disposed vertically or horizontally. The shoe is placed on the last with the sole thereof in engagement with the under surface of said last. The lever 36 is swung downwardly for clamping the sole of the shoe between the upper surface of the anvil and the under surface of said last. As the lever is moved downwardly, and the last forces the shoe against the anvil, the arm 38 and link 39 will shift the stem 32 upwardly against the tension of the spring 35. As previously described, when in full downward position, the pivot bolt 40 will be disposed slightly past dead center so that the spring may exert full downward pressure on the last for clamping the shoe in place on the anvil. The anvil, of course, is heated by connecting the electrical current source to the heating element. After heating of the heating element to a desired temperature, it will be possible to effect the cementing of a new sole or tap in place, as fully explained in my patent, No. 2,129,437. After the repair job has been completed, it is only necessary to shift the manually engageable portion 37 for raising the lever 36 and lifting the plunger 24. After the plunger 24 has been raised to its full uppermost limit, the pin 25 will clear the slot 23 and will permit the head to be rocked rearwardly for raising the element 30 to the position shown in dotted lines in Figures 2 and 7, whereupon the repaired shoe may be quickly and easily removed.

Attention is directed to the fact that, although I have shown but two heads and their associated structure, it should be understood that more may be employed if desired.

It is also desired to mention that the last 31 may be of the configuration shown, or may be of a size adapting it particularly for use for cementing patches on shoe toes.

The invention is characterized by the utmost simplicity and durability. The head construction has been considerably improved so that it is highly efficient but yet extremely compact. Moreover, inasmuch as means for resiliently urging the plunger downwardly is carried in the head, any type of last may be employed, a spring last not being required.

It is believed that further description is unnecessary.

Having thus described the invention, what is claimed as new is:

1. In a shoe repairing machine, a base, a standard carried by the base, a head carried by the standard, a shoe supporting element, an anvil

carried by the base beneath the shoe supporting element, a plunger carried by the head and operatively connecting the shoe supporting element with the head, an operating lever, resilient means carried by the head, and means connecting the operating lever with the plunger and resilient means, said last-mentioned means being operable for shifting the shoe supporting element downwardly and against the tension of the resilient means for clamping the sole of a shoe on the shoe supporting element between said element and the anvil.

2. In a shoe repairing machine, a base, a standard on the base, an anvil carried by the base, a head pivotally mounted on the standard, a shoe supporting element, a plunger carried by the head and operatively connecting the shoe supporting element with said head, a stem carried by the head, a spring about the stem, an operating lever, means operatively connecting the operating lever with the plunger and the stem, and means carried by the plunger for normally limiting the head to rest in vertical position, said operating lever being shiftable in one direction and against the tension of the spring for clamping the sole of a shoe between the shoe supporting element and the anvil and in another direction for raising the shoe supporting element to clear the anvil, said operating lever being further movable for clearing the last-mentioned means and permitting shifting of the head about the pivotal connection whereby the shoe supporting element will be disposed for permitting ready removal of a repaired shoe.

3. In a machine of the class described, the combination with a base having a standard having an end plate, a head, means pivotally connecting the head with the end plate, said end plate having an arcuate face and a straight edge, said head having an opening provided with a slot, one edge of said slot normally alining with the straight edge, a shoe supporting element, a plunger carried slidably in the head and operatively connecting the shoe supporting element with the head, a pin carried by the plunger and normally movable in the slot, resilient means carried by the head, an operating lever, means operatively connecting the operating lever with the plunger and the resilient means, and an anvil carried by the base, said operating lever being movable in one direction for shifting the plunger and shoe supporting element for clamping a shoe sole between the anvil and said shoe supporting element under the tension of the resilient means, said operating lever also being movable in the opposite direction for raising the plunger and the shoe supporting element and freeing the shoe sole from between said element and anvil, said lever being further movable in the last-mentioned direction for clearing the pin from the slot and the straight edge whereby said pin will be permitted to travel over the arcuate surface as the head is shifted on the pivotal means for disposing the shoe supporting element to a position for convenient removal of the shoe.

4. In a shoe repairing machine, a base having a standard formed with a bracket, said bracket having an end plate formed with a front face, an arcuate face, and a shoulder, a head, means pivotally connecting the head with the end plate, said head having an opening formed with a slot having an inner end normally alined with the front face of the plate, a plunger carried slidably in the opening of the head, a pin carried by the plunger and normally movable within the slot,

a shoe supporting element carried by the plunger, resilient means carried by the head, an operating lever, and means operatively connecting the operating lever with the plunger and with the resilient means, said plunger being shiftable in one direction for clamping a shoe sole beneath the shoe supporting element and under tension of the resilient means, said operating lever being movable initially in the opposite direction for raising the shoe supporting element, said operating lever being further movable for clearing the pin from the slot whereby said pin may be shifted along the arcuate face upon shifting of the head about the pivot means for engaging the pin with the shoulder and disposing the shoe supporting element to a position for permitting convenient removal of a shoe thereon.

5. In a shoe repairing machine as recited in claim 4, wherein the resilient means includes a stem, a collar on the stem, and a spring about the stem between the collar and a portion of the head.

6. In a shoe repairing machine, a head, means pivotally connecting the head with a bracket, said head having an opening and a recess, a plunger slidable in the opening, a stem shiftable in the recess, a collar on the stem, a spring between the collar and the upper limits of the recess, said head having a front wall formed with a slot receiving a portion of the collar therethrough, a shoe supporting element, means operatively connecting the shoe supporting element with the plunger, an operating lever, means pivotally connecting the operating lever with the plunger, and a link having one end connected with the collar and the other end connected with the operating lever, said link having an offset

lug, said operating lever being movable in one direction for clamping a shoe sole beneath the element under the tension of the spring, said tension being communicated to the element and plunger through the collar and link and said operating lever, said stem being shiftable against the tension of the spring, said operating lever being movable in an opposite direction for shifting the shoe supporting element to free a shoe sole from beneath said element, said lug permitting shifting of the operating lever past dead center.

7. In combination with a base having a standard provided with a web having flanges, and insulated studs carried by the flanges, an anvil having a frame formed with a depressed portion defining a well, said depressed portion having a thickened bottom wall formed with a recess, a heating element in the recess, contact springs electrically connected with the recess and being 15 removably engageable with the studs, and a resilient tread carried by the frame in overhanging relation to the well and liquid therein, said tread defining a resilient surface for a shoe being repaired.

8. In a shoe repairing machine, a base, a standard on the base, a head on the standard, a shoe supporting element, means carried by the head and operatively connecting the head with the shoe supporting element, resilient means carried by the head, and an operating lever pivotally mounted on the head and operatively connected with the shoe supporting element and said resilient means, said lever being shiftable 20 for clamping a shoe above the base and against the tension of said resilient means.

HARRY R. MYERS.
